poration of Illinois

Application December 17, 1946, Serial No. 716,855

7 Claims. (Cl. 250—20)

1

The present invention relates to loop-antenna tuning systems and, particularly, to such systems in which a loop-antenna circuit is tuned to any selected operating frequency within a wide range of such frequencies.

In recent years, it has become the practice to utilize loop antennas rather extensively with broadcast receivers. The loop antennas heretofore used frequently have been of the high-impedance type in which the loop-antenna inductance constitutes the entire inductance of a first radio-frequency tuned circuit of the receiver. In many cases, however, loop antennas of the low-impedance type, in which the loop-antenna inductance is generally a small part of the total inductance of the first radio-frequency tuned circuit, can yield superior performance and may result in a more economical design.

As will presently be explained more fully, the problems presented in connection with the tuning of antenna systems utilizing high-impedance loop antennas are quite different from those encountered in antenna systems employing low-impedance loop antennas. Many of these problems are largely avoided in the loop-antenna tuning system of the present invention which is adapted to use either a high-impedance or low-impedance loop antenna as desired. To understand the matter more fully, the relative merits of the high-impedance and low-impedance loop antennas will first be briefly considered following which the limitations and disadvantages inherent in prior loop-antenna tuning systems utilizing such antennas will be discussed.

There are several factors influencing the choice of a high-impedance or low-impedance loop antenna in a particular application. In free space, a high-impedance loop antenna usually will provide a performance superior to a low-impedance loop antenna having the same volume. By the term "volume" is meant the product of the cross-sectional area and depth of the antenna; it is the cubic content of space enclosed by the antenna. The effective volume of a loop antenna helically wound with its conductor turns in a plane, commonly called a "pancake" loop antenna, is that of an equivalent solenoid type of antenna in which each conductor turn has the same cross-sectional area as any other conductor turn and the several turns are wound in longitudinal depth. In practice, however, loop antennas can seldom be located in the equivalent of free space and, further, high-impedance loop antennas can rarely be constructed fully to utilize the available volume. A low-impedance loop antenna may thus be preferable where the effective area of a low-impedance loop can be appreciably greater than the effective area of a high-impedance loop. The "effective area" of a solenoid type of loop is its cross-sectional area; that of a pancake loop is

2

the cross-sectional area of its equivalent loop antenna. Thus in the case of large receivers of the console type, a low-impedance loop antenna can utilize the entire cabinet area whereas a high-impedance loop antenna is limited in size by other considerations. For example, if a high-impedance loop antenna has a large effective area, the inductance and capacitance tolerances are difficult to control to the required degree and the distributed capacitance may be too great to permit the loop-antenna system to be tuned over the desired band of wave-signal frequencies in the absence of a special and perhaps costly type of tuning condenser.

15 The low-impedance type of loop antenna may also be desirable in those applications where the effective Q, or ratio of inductive reactance to resistance, of the high-impedance loop is seriously impaired by its close proximity to the metallic 20 chassis of the receiver or other metallic objects or seriously changes when the loop is moved with respect to such chassis during operation, both of which conditions are frequently encountered in the case of portable receivers. Further, and 25 equally important, movement of the loop antenna with respect to the chassis as last mentioned in general will cause detuning of the loop-antenna system to an extent usually much more serious in the case of the high-impedance loop antenna than with the low-impedance loop antenna. Low-impedance loop antenna thus provide lesser variations of Q and detuning where the loop antenna is normally movably positioned with respect to a metallic chassis or other metallic object.

30 35 The low-impedance loop antenna for certain applications may have additional advantages over the high-impedance type of loop antenna. Thus, the low-impedance loop is less susceptible to electrostatic pickup than is the high-impedance loop and consequently will produce less noise disturbances in the receiver when operated in a region of appreciable electrostatic disturbances. Additionally, the low-impedance loop antenna is generally more directional than the high-impedance 40 loop antenna due to the lower electrostatic pickup of the former. A low-impedance loop antenna also has the advantage that it usually facilitates receiver alignment and servicing because it can be fastened directly around the inside of the receiver cabinet and will not interfere with access to the receiver tubes, trimmer condensers, and the like, and also because it does not require a fixed position with respect to the receiver chassis in order to maintain tracking of those receiver 45 50 tuned circuits which are tunable by a unicontrol mechanism.

The several enumerated advantages of the low-impedance loop antenna are offset to a great extent by the difficulty of attaining with it either or both a reasonably high figure of merit or a uni-

form figure of merit over a desired tuning band. The term "figure of merit" is conventionally defined as the ratio of voltage developed across the condenser of a parallel-resonant circuit coupled to or comprised by the loop antenna to the field strength of a received wave signal expressed in volts per meter. It is a measure of the effectiveness with which a wave signal of given field strength is picked up by the antenna and applied to the first amplifier tube of the receiver.

A high-impedance loop-antenna system is usually tuned over a desired wave-signal band in a rather simple manner by the use of a variable condenser coupled across the terminals of the loop antenna to provide therewith a parallel-resonant circuit constituting the input resonant circuit of the receiver. At resonance, the voltage appearing across the tuning condenser is equal to Qe , where Q is related to the resonant circuit comprised by the loop antenna and its tuning condenser, and is usually that of the loop antenna itself, and e is the wave-signal voltage induced in the loop by a received wave signal. Since, however, for a given value of field strength of the received wave signal and a constant value of Q the voltage induced in the loop varies directly with the frequency of the wave signal, the figure of merit of the loop-antenna system is proportional to the frequency of the received wave signal. This is undesirable for many applications for the reason that the signal-to-noise ratio of a receiver operating to receive relatively distant stations varies directly with the figure of merit of the antenna system and thus may be low at the low-frequency end of the tuning band and much higher at the high-frequency end of the band. It is consequently usually desirable that the figure of merit of a loop-antenna system be high and remain substantially constant over the desired tuned range, which is conventionally of the order of approximately three to one, in order to maintain a uniformly high signal-to-noise ratio. In practice the Q of a high-impedance loop-antenna system of the type described may be made to decrease at the high-frequency end of the tuning band to cause the figure of merit to remain more nearly constant over the tuning range. This has the disadvantage, however, that it is usually possible at best only to decrease the Q at the high-frequency end of the tuning band with the result that the figure of merit is usually reduced over most of the band. There is the further disadvantage that reducing the Q as described impairs the selectivity undesirably over an appreciable portion of the tuning band and causes the image ratio of a superheterodyne receiver to be impaired, the image ratio being defined as the ratio with which a desired wave signal is received on tune to that of a wave signal having an image frequency. Lastly, the figure of merit of a high-impedance loop-antenna system may undesirably vary simply by change of the loop Q caused by movement of the loop relative to the receiver chassis or other metal object as earlier mentioned.

A low-impedance loop antenna, on the other hand, frequently is utilized in a loop-antenna system which is tuned by adjustment of a relatively large inductor. The latter is included in series with the loop antenna and with a small fixed condenser to provide a resonant circuit usually comprising the input resonant circuit of the receiver. The wave-signal voltage developed across the condenser is again equal to Qe as in the arrangement first described. Since the induced voltage e varies with frequency as mentioned above, the

figure of merit of this system also is proportional to the wave-signal frequency for a given value of Q and a given field strength of the received wave signal. If the high-impedance and low-impedance loop-antenna systems described are to tune over the same tuning range, it is apparent that the impedance of the low-impedance loop antenna must be smaller than that of the high-impedance loop antenna by the value of the series tuning inductor. Of the composite inductance provided by the low-impedance loop antenna and the tuning inductor, the amount of inductance provided by the loop antenna depends upon the magnitude of the change of inductance which can be obtained by adjustment of the tuned inductor. The greater the change of inductance in the latter, or in other words, the greater the excess tuning range provided thereby, the greater can be the loop inductance and the higher will be the figure of merit of the antenna system.

The relative figures of merit of the high-impedance and low-impedance antenna systems described can be directly compared. If the capacitance of the low-impedance loop system is equal to the minimum capacitance of the high-impedance loop system, if both loop antennas have the same effective area and shape, and if both antenna systems have the same net value of resonant-circuit Q , the reduction D of the figure of merit of the low-impedance system as compared to the figure of merit of the high-impedance loop-antenna system at a given wave-signal frequency is given by the relation:

$$D = \sqrt{\frac{M_L - M_f}{M_L - 1}} \quad (1)$$

where

M_L is the available ratio of maximum to minimum inductance of the series tuning inductor; and, M_f is the ratio of maximum to minimum inductance required to tune the system over a desired wave-signal band.

If the same net value of resonant-circuit Q is assumed for the high-impedance and low-impedance loop-antenna systems, it will be apparent from Equation 1 that the low-impedance system utilizing the series tuning inductor has a uniformly lower figure of merit than does the high-impedance loop-antenna system over the tuning band. This variation of the figure of merit over the tuning band is undesirable, as earlier mentioned, and the impaired figure of merit of the low-impedance antenna system as compared to the high-impedance system works a substantial disadvantage favoring the latter system. Even if the Q of the low-impedance system were made to vary to improve the uniformity of its figure of merit over the tuning band, the Q would have to vary in the order of three to one across the band to maintain the figure of merit substantially constant and the average value of Q may then be rather low with a resultant low value of the figure of merit and greatly impaired selectivity of the antenna system.

To avoid the disadvantages mentioned of the antenna systems above described, it has been proposed that the figure of merit of a loop-antenna system be maintained substantially constant over the tuning band by the use of a low-impedance loop antenna with a series tuning inductor but including an adjustable inductor coupled directly across the terminals of the loop antenna and adjusted simultaneously with the adjustment of the series inductor. If this ar-

arrangement is assumed to have the same value of net resonant-circuit Q as in the low-impedance loop-antenna system last described and both are assumed to have constant Q across the tuning band and to have the same values of M_1 and M_2 , the figure of merit of the last-mentioned proposed arrangement remains substantially constant over the tuning band and is approximately equal to the figure of merit of the earlier described low-impedance system at the geometric mean frequency of the band. In practice, however, the figure of merit of the last-mentioned proposed arrangement is likely to be not higher than the lowest value of the figure of merit of the high-impedance loop-antenna system first described. Such a low value of figure of merit is undesirable from the standpoint that it results in an antenna system having a substantially lower signal-to-noise ratio than can be tolerated in many applications.

It is an object of the present invention, therefore, to provide a new and improved loop-antenna tuning system which avoids one or more of the disadvantages and limitations of prior such systems.

It is a further object of the invention to provide a loop-antenna tuning system which is characterized not only by a substantially constant figure of merit with tuning of the system over a relatively wide range of operating frequencies, but also one having a value of figure of merit substantially larger than heretofore readily obtainable in a system having a constant figure of merit.

It is an additional object of the invention to provide a new and improved loop-antenna tuning system which may utilize either a high-impedance or low-impedance loop antenna as desired.

In accordance with a particular form of the invention, a loop-antenna tuning system comprises: an inductor; a loop antenna effectively coupled across at least a portion of the inductor to provide therewith a composite value of inductance; and a condenser, including a capacitance-adjusting element, coupled across the inductor to provide a parallel-resonant circuit having a predetermined Q at a frequency within a range of operating frequencies. The system also includes an inductance-adjusting element, associated with the inductor and mechanically coupled to the capacitance-adjusting element for movement in unison therewith to tune the aforementioned circuit over the operating range, having a configuration and movement so related to the configuration and movement of the capacitance-adjusting element as to maintain over the operating range a ratio of composite inductance to capacitance for the circuit varying in opposite sense to any variation of Q thereof from the aforementioned value Q to maintain the figure of merit of the system substantially constant with tuning of the system.

For a better understanding of the present invention, together with other and further objects thereof, reference is had to the following description taken in connection with the accompanying drawing, and its scope will be pointed out in the appended claims.

Referring now to the drawing, Fig. 1 is a circuit diagram, partly schematic, of a complete wave-signal receiver which includes a loop-antenna system embodying the present invention; Fig. 1a represents the equivalent circuit diagram of the Fig. 1 antenna system and is utilized as an

aid in explaining its operation; Fig. 2 is a circuit diagram representing a modified form of the invention; Fig. 3 illustrates, partly schematically, the construction of a loop-antenna tuning system of the Fig. 2 type; and Fig. 4 illustrates a modified form of construction similar to that of Fig. 3.

Referring now more particularly to Fig. 1 of the drawing, the loop-antenna tuning system there shown comprises an inductor 10 and includes a loop antenna 11 coupled across the inductor 10 to provide therewith a composite value of inductance. As will presently be described more fully, the inductor 10 has its inductance varied to aid in tuning the antenna system over a range of operating frequencies. Since the inductance of the antenna 11 is effectively coupled in parallel with that of inductor 10 and since only the inductance of the latter is varied for tuning purposes, the coupling of the loop antenna to the inductor 10 reduces the range over which the composite inductance of the antenna and inductor may be varied. For a three-to-one range of operating frequencies and assuming that the Q or ratio of inductive reactance to resistance of the system remains constant over the tuning range, it is desirable in accordance with the present invention to attain a three-to-one range of variation of the composite inductance. This may be accomplished by so constructing the inductor 10 as to attain as large an inductance variation as possible and by then selecting for the loop antenna 11 an effective value of inductance which with the inductor 10 provides a resultant three-to-one inductance variation. Since the value of loop inductance required to do this is usually rather high, a loop antenna constructed to provide that value of inductance would be unduly expensive because of the requirements that the distributed capacitance of the loop preferably be kept low and its Q be kept high. Consequently, it is more desirable in a practical application of the invention to construct the loop antenna 11 to have a medium value of inductance and then to couple it to the inductor 10 in a manner hereinafter described in connection with a modified form of the invention in which the value of loop inductance is transformed effectively to the much higher value desired.

The antenna tuning system also includes a condenser 13, having a capacitance-adjusting element, coupled across the inductor 10 to provide a parallel-resonant circuit having a predetermined Q at a frequency within a range of operating frequencies. Preferably, the value of Q of the parallel-resonant circuit 10, 13 remains substantially constant at any frequency within the range of operating frequencies.

The tuning system also includes an inductance-adjusting element 14 associated with the inductor 10 and mechanically coupled to the capacitance-adjusting element of the condenser 13, as indicated in broken lines, for movement in unison therewith to tune the parallel-resonant circuit 10, 13 over the aforementioned range of operating frequencies. The inductance-adjusting element 14 has a configuration and movement so related to the configuration and movement of the capacitance-adjusting element of the condenser 13 as to maintain over the aforementioned range of operating frequencies a ratio of composite inductance to capacitance for the parallel-resonant circuit varying in opposite sense to any variation of Q thereof from the aforementioned predetermined value of Q to maintain

the figure of merit of the loop-antenna tuning system substantially constant with tuning of the circuit 10, 13. Where the Q of the parallel-resonant circuit is constant over the tuning range, the ratio of composite inductance to capacitance is then approximately constant. In practice, however, it may be difficult to maintain constant Q with tuning in which event it is preferable that the ratio of composite inductance to capacitance be made to vary inversely proportional to the square of the variations of Q . The inductance-adjusting element 14 comprises a magnetic member, for example a powdered-iron core, movably positioned in the magnetic field of the inductor 10. To obtain a large variation of inductance, and incidentally to retain a substantially constant Q , of the parallel-resonant circuit 10, 13 over the tuning range, the inductor 10 preferably has an effective length much greater than its diameter. The element 14 then has a length comparable to that of the inductor 10 to effect a reasonably linear adjustment of the inductance thereof with movement of the element and thus a composite inductance for the inductor 10 and loop antenna which tends to have an approximately linear inductance variation. Assuming a constant value of Q with tuning, the capacitance-adjusting element of the condenser 13 correspondingly has a configuration to provide a linear adjustment of the capacitance of the condenser with movement of the latter element. Movement of the inductance-adjusting element 14 and the capacitance-adjusting element last mentioned then effects simultaneous and substantially linear adjustments of the composite inductance of the inductors 10 and 11 and the capacitance of the condenser 13 to maintain over the tuning range a substantially constant ratio of composite inductance to capacitance as is desirable for constant Q .

The loop-antenna tuning system above described is coupled to the input circuit of a wave-signal receiver 15, usually being coupled directly to the input electrodes of the first vacuum tube employed in the receiver.

Considering now the operation of the loop-antenna tuning system just described, wave-signal energy received by the loop antenna 11 is applied to the parallel-resonant circuit 10, 13. The latter is tuned to resonance, by simultaneous adjustments of the inductance-adjusting element 14 and the capacitance-adjusting element of the condenser 13, with the received wave-signal energy, and the wave-signal potentials developed across the circuit are applied to the input circuit of the receiver 15 for utilization thereby in a conventional manner.

The operation of the antenna system will now further be considered with reference to Fig. 1a which represents the equivalent circuit of the loop-antenna tuning system. In this equivalent circuit, the inductor L_a represents the equivalent parallel inductance of the loop antenna 11 and the inductor 10 and is given by the relation:

$$L_a = \frac{L_b L_c}{L_b + L_c} \quad (2)$$

where

L_b =the inductance of the loop antenna 11; and L_c =the inductance of the inductor 10.

A wave-signal voltage e_1 is induced in the loop antenna 11 by a received wave signal. The resulting voltage e of the equivalent circuit is given by the relation:

$$e = e_1 \cdot \frac{L_c}{L_b + L_c} \quad (3)$$

The voltage E_c developed across the condenser 13 by the equivalent voltage e is given by the relation:

$$E_c = Q_e \quad (4)$$

where

Q =the value of the net resonant-circuit Q which is usually the composite Q of the loop antenna 11 and inductor 10 in parallel.

From Equations (2) and (3), the equivalent voltage e is thus given by the relation:

$$e = e_1 \cdot \frac{L_b L_c}{L_b + L_c} \left(\frac{1}{L_b} \right) = e_1 \cdot \frac{L_c}{L_b} \quad (5)$$

However, the induced voltage e_1 of the loop-antenna system is also given by the relation:

$$e_1 = K \omega E \quad (6)$$

where

K =an arbitrary constant

ω =the angular frequency of the received wave signal

E =the field strength of the received wave signal.

The figure of merit of the antenna system is thus seen from Equations 4, 5 and 6 to have the value:

$$\frac{E_c}{E} = \frac{K}{L_b} Q \omega L_a \quad (7)$$

The value of inductance of the inductor L_a and the value of capacitance C of the condenser 13 when these elements are tuned to resonance with the received wave signal are expressed by the relation:

$$35 \quad \omega = \frac{1}{\sqrt{L_a C}} \quad (8)$$

From Equations 7 and 8, the figure of merit of the antenna system may be expressed by the relation:

$$40 \quad \frac{E_c}{E} = \left(\frac{K}{L_b} \right) Q \sqrt{\frac{L_a}{C}} \quad (9)$$

It will be apparent from Equation 9 that for a constant value of the figure of merit, the ratio of the composite inductance to the capacitance of the loop-antenna system must vary inversely proportional to the square of any variations of the Q thereof; that is,

$$50 \quad \frac{L_a}{C} \propto \frac{1}{Q^2} \quad (10)$$

It is evident from the last-mentioned relationship that the ratio of composite inductance to capacitance of the antenna system should remain constant with tuning if the value of the net resonant-circuit Q of the system is to remain constant over the tuning band. In practice, the Q of the system usually will vary somewhat over the tuning band, in which case the ratio of composite inductance to capacitance of the system should vary in opposite sense with variations of Q to maintain the figure of merit substantially constant and particularly the ratio mentioned should vary as the square of such variations of Q . The ratio of composite inductance to capacitance may be caused to vary as last described by suitable choice of the configuration and related movements of the inductance-adjusting element 14 and the capacitance-adjusting element of the condenser 13. Ordinarily this is not difficult and may perhaps be most readily accomplished by suitably shaping the plates of the condenser 13 to provide a desired mode of variation of the capacitance thereof.

Fig. 2 is a circuit diagram representing an additionally modified form of the invention essen-

tially similar to that of Fig. 1, similar elements being designated by similar reference numerals and analogous elements by similar reference numerals primed, except that the loop antenna 11, of the present arrangement is constructed to have a relatively low impedance and is coupled only across a portion of the inductor 10'. As thus arranged, the inductor 10' operates in the nature of an auto-transformer so that the inductance of the loop antenna 11 is effectively increased to the desired value by suitable selection of the relative value of the inductor portions *a* and *b*. As will presently be described in more detail, the inductor 10' of the present arrangement preferably has the inductor portion *a* wound over the inductor portion *b*, the two inductor portions being connected to have aiding magnetic fields. This construction of the inductor 10' ensures that both inductor portions are tightly coupled for all positions of movement of the inductance-adjusting element 14. Optimum system performance is obtained by so selecting the relative inductances of the loop antenna 11 and inductor 10' that the portions *a* and *b* of the latter are approximately equal. The present arrangement has the important advantage, in addition to its simplicity and the fact that it involves a relatively inexpensive construction, that the wave-signal currents flowing in the circuit of the antenna 11 are in opposing phase to those flowing in the parallel-resonant circuit 10', 13 so that very little wave-signal current flows through the portion *a* of the inductor 10'. This permits the inductor portion *a* to be constructed of relatively fine wire where desired, thereby to permit the inductor portion *b* to be constructed of heavier wire with consequent improvement of the Q of the inductor 10' and of the parallel-resonant circuit in which it is used. The operation of this modified form of the invention is otherwise essentially similar to that hereinbefore described and will not be repeated.

Fig. 3 illustrates, partly schematically, a suitable form of construction of the inductor 10' and condenser 13 of the Fig. 2 arrangement, elements in Fig. 3 corresponding to similar elements of Fig. 2 being designated by similar reference numerals. The inductor 10' is wound upon a suitable cylindrical form 16 of insulating material, the inductor portion *a* being wound with relatively fine wire 17 over the inductor portion *b* which is wound with much heavier wire 18. Preferably the portion *a* is wound over a separate winding form, not here shown for simplicity, which is then positioned in telescoped relation to the portion *b* wound on the form 16. The length of the inductor 10' is much greater than its diameter, and the inductance-adjusting element 14 is constructed as a solid cylinder of magnetic material, such as powdered iron, of length comparable to that of the inductor and of a diameter to permit the element to be easily moved within the coil form 16. This construction provides a substantial variation of inductance with movement of the element 14. The condenser 13 comprises two stationary condenser plates 19, 20 and a movable plate 21 with dielectric material 22 inserted therebetween. This condenser construction, as is well known, is one which may if desired be arranged to provide a linear variation of capacitance with movement of the condenser plate 21 or may easily be arranged to provide any other desired manner of capacitance variation. The movable inductance-adjusting element 14 and the movable condenser plate 21 are mechan-

ically connected for unicontrol adjustment by a member 23.

Fig. 4 illustrates a modified form of construction suitable for the tunable elements of a loop-antenna tuning system embodying the present invention. Elements of Fig. 4 corresponding to similar elements of Fig. 3 are designated by similar reference numerals and analogous elements by reference numerals primed. The condenser 13' includes cylindrical stationary condenser plates 19', 20' supported in concentric relation and electrically connected together at one end by a conductive disc 24. The condenser plate 21' also is of cylindrical configuration and is arranged to move into telescoping relation with the stationary condenser plates 19', 20'. The condenser plate 21' is closed at one end by a conductive disc 25 and the inductance-adjusting element 14 is supported by an insulating member 26 from the disc 25 and in coaxial relation therewith. As thus supported, the element 14 moves with the condenser plate 21' into telescoping relation with the inductor 10' coaxially supported by its coil form 16 from the disc 24. The present construction provides a substantial, and if desired linear, variation of inductance of the inductor 10' and is readily adapted to provide any desired manner of variation of capacitance of the condenser 13'. In addition, it has the important advantage that the inductor 10' is effectively enclosed within a shielding housing provided by the condenser 13', thus to confine the wave-signal fields of the parallel-resonant circuit 10', 13' within the condenser 13'. Since a high figure of merit is desirable in a loop-antenna tuning system embodying the present invention, and since the value of the figure of merit varies directly with the Q of the inductor 10', the condenser plates 19', 20' should have sufficient diameters that they do not unduly impair the Q of the inductor by their proximity thereto.

As illustrative of a specific embodiment of the invention, the following circuit constants are given for an embodiment of the invention of the type shown in Fig. 2:

Loop antenna	194 microhenries
Effective inductance of antenna 11 as coupled across the parallel-resonant circuit 10', 13'	960 microhenries
Inductor 10'	320 to 2860 microhenries (9 to 1 range of variation)
Portion <i>a</i>	215 turns No. 7/44 SCE Litz wire progressive universal wound on coil form 0.335 inch O. D. Bakelite; inductance=111 microhenries in air, Q=71
Portion <i>b</i>	265 turns No. 7/44 SCE Litz wire progressive universal wound on coil form 0.223 inch O. D. Bakelite; inductance=80 microhenries in air, Q=80
Composite inductance of loop antenna 11 and inductor 10' in parallel	240 to 720 microhenries (3 to 1 range of variation)
Condenser 13	40 to 120 micromicrofarads (3 to 1 range of variation)
Tuning range of antenna system	550 to 1650 kilocycles
It should be noted in connection with these representative circuit constants that while the value of the loop-antenna inductance given is similar to that used with high-impedance condenser-tuned loop circuits, the loop antenna 11 is de-coupled from the circuit 10', 13 and thus has many of the advantages of low-impedance loop circuits.	
From the foregoing description of the invention, it will be apparent that a loop-antenna tuning system embodying the invention has the	

advantage that it exhibits a substantially constant and high figure of merit with tuning of the system over a relatively wide range of operating frequencies. There is the additional advantage that the figure of merit obtainable may have a value substantially larger than heretofore readily obtainable where a constant figure of merit is of paramount importance.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A loop-antenna tuning system comprising: an inductor; a loop antenna effectively coupled across at least a portion of said inductor to provide therewith a composite value of inductance; a condenser, including a capacitance-adjusting element, coupled across said inductor to provide a parallel-resonant circuit having a predetermined Q at a frequency within a range of operating frequencies; and an inductance-adjusting element, associated with said inductor and mechanically coupled to said capacitance-adjusting element for movement in unison therewith to tune said circuit over said range, having a configuration and movement so related to the configuration and movement of said capacitance-adjusting element as to maintain over said range a ratio of composite inductance to capacitance for said circuit varying in opposite sense to any variations of Q thereof from said predetermined value of Q to maintain the figure of merit of said system substantially constant with said tuning of said circuit.

2. A loop-antenna tuning system comprising: an inductor; a loop antenna effectively coupled across at least a portion of said inductor to provide therewith a composite value of inductance; a condenser, including a capacitance-adjusting element, coupled across said inductor to provide a parallel-resonant circuit having a predetermined Q at a frequency within a range of operating frequencies; and an inductance-adjusting element, associated with said inductor and mechanically coupled to said capacitance-adjusting element for movement in unison therewith to tune said circuit over said range, having a configuration and movement so related to the configuration and movement of said capacitance-adjusting element as to maintain over said range a ratio of composite inductance and capacitance for said circuit varying approximately inversely proportional to the square of any variations of Q thereof from said predetermined value of Q to maintain the figure of merit of said system substantially constant with said tuning of said circuit.

3. A loop-antenna tuning system comprising: an inductor; a loop antenna effectively coupled across at least a portion of said inductor to provide therewith a composite value of inductance; a condenser, including a capacitance-adjusting element, coupled across said inductor to provide a parallel-resonant circuit having a predetermined substantially constant value of Q at any frequency within a range of operating frequencies; and an inductance-adjusting element, associated with said inductor and mechanically coupled to said capacitance-adjusting element for

movement in unison therewith to tune said circuit over said range, having a configuration and movement so related to the configuration and movement of said capacitance-adjusting element as to maintain over said range a substantially constant ratio of composite inductance to capacitance for said circuit to maintain the figure of merit of said system substantially constant with said tuning of said circuit.

4. A loop-antenna tuning system comprising: an inductor; a loop antenna effectively coupled across at least a portion of said inductor to provide therewith a composite value of inductance; a condenser, including a capacitance-adjusting element, coupled across said inductor to provide a parallel-resonant circuit having a predetermined Q at a frequency within a range of operating frequencies; and a magnetic member, movably positioned in the magnetic field of said inductor and mechanically coupled to said capacitance-adjusting element for movement in unison therewith to tune said circuit over said range, having a configuration and movement so related to the configuration and movement of said capacitance-adjusting element as to maintain over said range a ratio of composite inductance to capacitance for said circuit varying in opposite sense to any variations of Q thereof from said predetermined value of Q to maintain the figure of merit of said system substantially constant with said tuning of said circuit.

5. A loop-antenna tuning system comprising: an inductor; a loop antenna effectively coupled across at least a portion of said inductor to provide therewith a composite value of inductance; a condenser, including a capacitance-adjusting element, coupled across said inductor to provide a parallel-resonant circuit having a predetermined Q at a frequency within a range of operating frequencies; and a powdered iron core, movably positioned in the magnetic field of said inductor and mechanically coupled to said capacitance-adjusting element for movement in unison therewith to tune said circuit over said range, having a configuration and movement so related to the configuration and movement of said capacitance-adjusting element as to maintain over said range a ratio of composite inductance to capacitance for said circuit varying in opposite sense to any variations of Q thereof from said predetermined value of Q to maintain the figure of merit of said system substantially constant with said tuning of said circuit.

6. A loop-antenna tuning system comprising: an inductor having an effective length much greater than its diameter; a loop antenna effectively coupled across at least a portion of said inductor to provide therewith a composite value of inductance; a condenser, including a capacitance-adjusting element, coupled across said inductor to provide a parallel-resonant circuit having a predetermined Q at a frequency within a range of operating frequencies; and a magnetic member, having a length comparable with that of said inductor, associated with said inductor and mechanically coupled to said capacitance-adjusting element for movement in unison therewith to tune said circuit over said range, and having a configuration and movement so related to the configuration and movement of said capacitance-adjusting element as to maintain over said range a ratio of composite inductance to capacitance for said circuit varying in opposite sense with any variations of Q thereof from said predetermined value of Q to maintain the figure of merit of said

13

system substantially constant with said tuning of said circuit.

7. A loop-antenna tuning system comprising: an inductor having two portions wound over one another with aiding magnetic fields; a loop antenna connected across one of said portions of said inductor to provide with said inductor a composite value of inductance; said one portion of said inductor being selected to provide a substantial effective increase of said antenna inductance; a condenser, including a capacitance-adjusting element, coupled across said inductor to provide a parallel-resonant circuit having a predetermined Q at said frequency; and an inductance-adjusting element, associated with said inductor and mechanically coupled to said capacitance-adjusting element for movement in unison therewith to tune said circuit over said range,

10

5

having a configuration and movement so related to the configuration and movement of said capacitance-adjusting element as to maintain over said range a ratio of composite inductance to capacitance for said circuit varying in opposite sense to any variations of Q thereof from said predetermined value of Q to maintain the figure of merit of said system substantially constant with said tuning of said circuit.
